Primary Examiner — Cynthia Ramirez*Assistant Examiner* — Michael A Maharajh(74) *Attorney, Agent, or Firm* — Craft Chu PLLC;
Andrew W. Chu(57) **CLAIM**

The ornamental design for a lid for a refuse receptacle, as shown and described.

DESCRIPTION

FIG. 1 is an upper perspective view of the lid for a refuse receptacle showing my design in an opened position; FIG. 2 is another upper perspective view thereof, showing the lid in a closed position;

FIG. 3 is a back elevation view in the opened position; FIG. 4 is a front elevation view in the closed position; FIG. 5 is a side elevation view thereof in the closed position, an opposite side elevation view being a mirror image thereof in the closed position; FIG. 6 is a top plan view thereof in the closed position; and, FIG. 7 is a bottom plan view thereof in the closed position.
